Primary Examiner — Marie D. Fast Horse*Assistant Examiner* — Josiah D. Parsons(74) *Attorney, Agent, or Firm* — Sterne, Kessler, Goldstein & Fox P.L.L.C.(57) **CLAIM**

The ornamental design for an optical scanner, as shown and described.

DESCRIPTION

FIG. 1 is a top perspective view of an optical scanner showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
